UNITED STATES PATENT OFFICE

2,692,376

CLAMP TYPE CONNECTOR

Harold A. Van Dusen, Jr., South Milwaukee, Wis., assignor to McGraw Electric Company, Milwaukee, Wis., a corporation of Delaware

Application October 25, 1951, Serial No. 253,139

2 Claims. (Cl. 339—249)

1

This invention relates to an improvement in washers and in particular to a cup-shaped washer to be used on a swinging clamp type connector for electrical power lines.

A swinging clamp U-bolt connector covered by U. S. Patent No. 2,432,635 issued to Anthony Van Ryan and assigned to the same assignee as this application, has proved to be an excellent connector for electric cables. It incorporates many desirable features to make it easier and safer for the lineman. Features such as allowing large conductors to pass freely between the legs of the U-bolt while the middle channel and the lower keeper channel are swung open and at the same time the tightening nuts and washers remain on their respective threaded legs of the U-bolt. Another feature is the positioning of the U-bolt at an angle of about 45° in respect to the conductors to allow longer channels to be used. This gives a longer bearing surface which provides greater clamping strength and alleviates the possibility of distorting the conductors.

However, certain difficulties have arisen. There is nothing other than friction to prevent the lower clamp channel from swinging out while it is being tightened and after it is in use. It is also desirable to strengthen the base to prevent enlargement of the opening.

The object of this invention is to overcome these difficulties by providing a cup-shaped washer which fits over a boss on the keeper hinge channel to lock it in place.

Another object of this invention is to provide a cup washer which adds strength to elongated or slot openings by holding the two sides together to prevent spreading.

Other objects will appear from time to time in the course of the specification and claims.

The embodiment that I illustrate is shown in connection with the U-bolt clamp type connector but it is to be understood that the invention is not limited to only this use.

Referring to the drawing:

Fig. 1 is a side elevation of the U-bolt clamp at a 45° angle to the conductors with part of the cup washer in section.

Fig. 2 is a bottom view of Fig. 1.

Fig. 3 is a bottom view of the U-bolt clamp with the middle channel and lower keeper channel swung out.

Fig. 4 is a view of the cup washer before it is fitted over the circular boss on the keeper member, taken approximately on the line 4—4 of Fig. 2.

2

Fig. 5 is a view of the cup washer in position on the boss, the cup washer in section, taken approximately on the line 5—5 of Fig. 2.

Like reference figures represent like parts throughout.

Referring to Fig. 4, my cup washer 1 consists of a circular flat base 2 with a circular opening 3 through its center for receiving a leg of the U-bolt, and a side wall 4 extending around the base 2 at right angles to the base. This wall 4 forms the cup shape which fits over a boss 5 on the lower keeper channel 6 of a U-bolt clamp connector 7.

In Fig. 1 I illustrate the U-bolt clamp connector 7 consisting of a U-bolt 8 and three main members. An upper member 9 has ears 10 which fit around the top of the U-bolt 8 to hold it in place and a channel 11 on its under surface to fit around the top of a conductor 12.

An intermediate member 13 has channels on both its upper and lower surfaces, the upper channel fitting around the lower side of the cable 12 and a lower channel 14 fitting over the upper surface of a second conductor 15. This intermediate member 13 is hinged around the leg 8a on one end corner and has a hook protrusion 16 at the other and opposite end corner that serves to position the member 13 between the cables 12 and 15 when the hook 16 contacts the leg 8b of the U-bolt 8.

The third main member 6 has a channel 17 on its upper surface which fits around the lower part of the cable 15. This lower member 6 is the keeper member of the clamp and is hinged on the leg 8a at one end. At the other end of member 6 is an elongated hook opening 18 that engages the leg 8b when in clamping position. Forming a collar around this opening 18 is the boss 5 extending downwardly from the bottom surface of the keeper 6. This boss 5 serves as the seating member for my cup-shaped washer 1.

By referring to the various Figs., especially Fig. 3, it can be seen that when my cup-shaped washer 1 seats on the boss 5 which surrounds the opening 18, it locks the swinging keeper member 6 in clamping position preventing it from swinging open when being tightened by nuts 19 and washers 20. The cup washer 1 by engaging the boss 5 adds strength to the base and prevents the elongated opening 18 from spreading and losing its hook quality.

The attributes of the clamp type connector are fully set forth in Anthony Van Ryan's Patent No. 2,432,635 and in use it has provided an excellent means of clamping two conductors together

or for providing a fastening means for dead ends. With my cup washer to insure against the clamp swinging open and to prevent spreading of the hook, the clamp type connector becomes a better device to give efficient and satisfactory service.

With this novel co-action between the hinged member, the bolt, and the cup-shaped washer, the clamp does not have to be tightened as much as in previous devices of this character, namely the Van Ryan patent above referred to. Over tightening tends to distort the hinge member, eventually rendering it unusable for further use. Over tightening also tends to lessen the bearing surface which reduces gripping strength. Therefore, it can be seen that with my cup-shaped washer in combination with the clamping device, I provide a needed improvement in clamp type connectors.

I claim:

1. In a clamp type connector of the U-bolt type for connecting a pair of conductors, said connector comprising three clamping members, a U-bolt having the bight portion thereof embracing the top clamping member, an intermediate member pivotally secured to one of the legs of said U-bolt, a lower member pivotally secured to one of the legs of said U-bolt having a slot therein to embracingly engage the other leg of said U-bolt, a raised boss portion about said slot, a mating washer having a marginal flanged portion cooperatively engaging said boss portion when said slotted lower member is brought into engagement with the other leg of said U-bolt, tightening means on both of said legs of said U-bolt to secure the conductors, the flanged washer and boss portion cooperating with said lower member to prevent movement towards disengagement of said lower member and said other leg when the conductors are secured thereby providing higher bearing pressures on the conductor 40 whereby a better electrical joint is secured.

2. In a clamp type connector of the U-bolt type for connecting a pair of conductors, said connector comprising three clamping members, a U-bolt having the bight portion thereof embracing the top clamping member, an intermediate member pivotally secured to one of the legs of said U-bolt, a lower member pivotally secured to one of the legs of said U-bolt having a slot therein to embracingly engage the other leg of said U-bolt, a raised boss portion about said slot, a mating washer having a marginal flanged portion cooperatively engaging said boss portion when said slotted lower member is brought into engagement with the other leg of said U-bolt, tightening means on both of said legs of said U-bolt to secure the conductors, the flanged washer and boss portion cooperating with said lower member to prevent movement towards disengagement of said lower member and said other leg when the conductors are secured thereby providing higher bearing pressures on the conductor 10 whereby a better electrical joint is secured, and cooperating lateral grooves in said three clamping members to accommodate the conductors positioned therebetween.
